UNITED STATES PATENT OFFICE

LESTER J. WILLIAMS, OF CANASTOTA, NEW YORK, ASSIGNOR TO CARL BRAUN INC., OF CANASTOTA, NEW YORK, A CORPORATION OF NEW YORK

CAN WASHING MACHINE

Application filed November 13, 1923. Serial No. 406,733.

My invention relates to machines for washing or sterilizing cans, of the general character disclosed in the application Serial No. 468,184 filed July 15, 1930, and particularly to new and improved means for supplying cans and covers to a washer such as that shown in said application.

The principal object is to provide conveying or feeding mechanism which may be connected with the feeding mechanism of the sterilizer and may be located in a receiving room, so that cans may be received and handled in the receiving room and placed on the present feed mechanism and by it automatically advanced to the sterilizer; and further to so arrange the feed mechanism that it may be moved to an inactive position, leaving the sterilizing machine free at its receiving end for placing cans and covers directly therein when the cans are not handled in the receiving room. The invention is in one aspect thus designed to comply with sanitary regulations in certain localities, which provide that city milk cans cannot be washed in a machine installed in a receiving room, although country cans may be washed or handled in such a room. My invention, including means for carrying out the objects just above stated, enables such regulations to be complied with, since country cans may be drained or otherwise handled in the receiving room and placed on the present feed mechanism therein, and by it automatically advanced to the washer or sterilizer located in its own room or compartment; and when handling city cans, the feed mechanism (or a movable part of it) may be moved back into the receiving room, or away from the receiving end of the sterilizer, and the cans handled only in the sterilizing room or compartment and placed directly in the sterilizer.

The characteristics and advantages of the invention are further sufficiently explained in connection with the following detail description of the accompanying drawings, which show representative embodiments. After considering these examples, skilled persons will understand that many variations may be made without departing from the principles disclosed, and I contemplate the employment of any structures that are properly within the scope of the appended claims.

Figure 1 is a diagrammatic side elevation of apparatus embodying the invention in one form;

Fig. 2 is a side elevation of the feed mechanism in one operative position or condition in relation to the sterilizing machine, the receiving end of which is shown;

Fig. 3 is a plan view;

Fig. 4 is a side elevation, enlarged, showing principally cover feed slides, connections, etc.; and

Fig. 5 is a detail, in side elevation, of a modification, providing for the hinging or movable mounting of the feed mechanism at the floor level.

In Figs. 1 and 2, 10 is a can washing or sterilizing machine of the type disclosed in the above mentioned application. It includes a frame 11, a portion 12 of which at the front or receiving end is arranged to receive the cans and covers which rest on guide rails 13, 14. The cans, in inverted position are advanced on the trackway including the rails 13, this being the lower trackway in the plan view, Fig. 3, by pawls 15 pivotally mounted on reciprocating bars or slides 16; and the covers are placed on rails 14 and advanced by pawls which are not shown, but are similar to the cover-advancing pawls of the present feed mechanism and are mounted on a reciprocating bar or slide 17. The slides 16 are located practically at the level of the top frame members 18, Fig. 1, and the slide 17 is located in an upper position above its corresponding cover-supporting rails. The details of the feed mechanism of the sterilizer proper 10, means for operating the slides, washing or scrubbing mechanism within the housing, and means for discharging the cans and covers, are fully explained in the application above mentioned.

In the preferred arrangement of a dairy or other depot in which cans are handled, the sterilizer is located adjacent a receiving room 20 which preferably has a floor 21 located at a level above that of floor 22 of the sterilizing room, or compartment in which the sterilizer is located, this elevated floor 100 being convenient for receiving cans of certain classes from trucks or wagons at the left of Fig. 1. This arrangement leaves a space 23 between the receiving room and the receiving end of the sterilizer, in which cans and covers of other classes may be handled and placed directly on the rails of the sterilizer above frame portion 12, and advanced into the sterilizer by its feed mechanism.

As an important feature of the invention,

the present feed mechanism is arranged to cooperate with the just-described arrangement of sterilizer and receiving room. The feed mechanism diagrammatically indicated 5 at 30 in Fig. 1 and shown in detail in Figs. 2 and 5, comprises longitudinal side frame members 31 and 32 connected by various cross members such as 33, Fig. 3. A part of the feed mechanism, represented by the part supported 10 by the frame members 31, is located in the receiving room and is supported on the floor thereof by legs 34. Another portion of the feed mechanism, carried by the frame members 32, extends from the frame members 31 to the sterilizing machine, the frame members 32 being provided with plates 35 having lugs or hooks 36 engaging a cross bar 37 on the forward or receiving frame portion 12 of the sterilizer. The frame members 15 32 are hingedly connected at 38 to the members 31, so that the entire frame section represented by the members 32 may be swung up to an inactive position, away from the sterilizer, and preferably into the receiving room 20, or may be placed in active position to feed cans and covers to the sterilizer as shown in Fig. 2, the frame members 32 being then aligned with similar side frame members of the sterilizer. 25 The frame members of the feed mechanism support rails 13 for can support and other rails 14 for cover support, corresponding to the similar rails of the sterilizer and aligned therewith, when the frame section 30 32 is in active position. The can feed mechanism also includes slides corresponding to the slides 16 of the sterilizer and arranged for reciprocation and for detachable connection to the sterilizer slides, and the cover feed 35 portion of the feed mechanism also includes a central elevated slide corresponding to slides 17 of the sterilizer and arranged for releasable connection thereto. In the particular arrangement shown in Figs. 2, 3 and 4, the 40 various slides of the feed mechanism are articulated, to permit a folding action corresponding to the folding movement of the frame section 32 when the feed mechanism is inactive. Thus, the can body feed slides consist of members 40 and 41 hingedly connected at 42, and the cover slide consists of members 43 and 44 hingedly connected at 45, and supported in guides in frame-uprights 44a. To fold the feed frame, the slides 40 and 41 may 45 be so positioned that their hinges 42 are substantially above the hinge 38 connecting frame members 31 and 32; and the slide section 44 may be folded back upon the slide 43 as shown in Figs. 2 and 4, thus admitting 50 the upward swinging of the feeder frame to an inactive position when the receiving room 20 has a low ceiling or when its doorway 20a is low. The slide section 44 may be secured in this inactive position by clamp or clip 46. 55 For the connection of the feeder slides to

the sterilizer slides when the feeder is in active condition, the can body slides 41 of the feeder have thereon swing-bolts 47 with nuts 48, and the sterilizer slides 16 have on their forward ends clevised brackets 49, so that the swing bolts may be engaged with the brackets and the feeder slides will then be operated by the sterilizer slides. Similarly, the cover feeding slide section 44 has a swing bolt 50 to engage with a clevised lug 51 on the forward end of the sterilizer slide 17, whereupon the cover feed mechanism of the feeder will be operated from the sterilizer. The swing bolts or other equivalent connections may be easily disconnected to release the feeder slides from the sterilizer slides when the feeder is to be placed in inactive position. The various feeder slide sections are provided with pawls which may be identical in arrangement and operation to the corresponding can and cover feed pawls of the sterilizer as above referred to. Thus, the feeder slides 40 and 41 carry horizontal pawls 15 corresponding to the pawls 15 of the sterilizer, and the cover feeding slide sections 43 and 44 of the feeder have depending cover feeding pawls 52 which may be identical with the cover feed pawls of the sterilizer, carried by the sterilizer slide 17 and not here shown, but fully shown and described in the above identified application. 95

Figs. 2 and 3 show the feed mechanism in active position except for connection of the can body slides to those of the sterilizer, and except for the swinging forward of the cover slide section 44 and connection to the sterilizer slide 17. The mode of connection of these members is sufficiently explained above, and as to the cover slide connection, this is shown in dotted lines in Fig. 4. 100

To place the feed mechanism in inactive position, the slides are disconnected; slide section 44 is placed in folded position, Figs. 2 and 4, the can body slides 41 are moved to position their hinge connections 42 above the frame hinges 38, and the frame is tilted up to inactive position away from the sterilizer and handling space 23, and usually within the receiving room; and cans may then be received and handled in the receiving space 23 directly to the sterilizer in accordance with regulations. 115

Fig. 1 shows a modification in which an entire feed mechanism may be swung up into the receiving room, without requiring foldable connection of its frame or slide members, the receiving room or its doorway 20a being arranged or dimensioned to permit this arrangement of the feed mechanism. In this case, the side frame members 31 of the feeder 120 30 may be continuous and not articulated and may be supported at their end remote from the sterilizer on the legs 60 which are pivotally connected to floor brackets 61 within the receiving room. 125

When the feed mechanism is in active position and connected to the sterilizer, cans of certain classes may be received directly in the receiving room, handled therein and

5 placed on the feed mechanism and automatically fed into and from the sterilizer without other handling, as will be obvious from the preceding description.

I claim:

10 1. The combination with a sterilizing device for cans and covers having a reciprocating slide for advancing the cans and a reciprocating member located above the can advancing slides for advancing the covers, 70
15 with auxiliary mechanism for use at the end of the can and cover sterilizing device comprising a reciprocating slide having a hinged connection to permit the remote end of the slide to be swung vertically, one end of the 80
20 slide member having means for connecting the slide of the auxiliary mechanism to the slide of the can advancing device and a slide arranged above the can advancing slides for advancing the covers, the cover advancing 85
25 slide being hinged to fold upon itself and having means to connect the cover advancing slide of the auxiliary mechanism and the cover advancing slide of the sterilizer, the cover advancing slide having a plurality of 90
30 dependent pivotally swinging cover engaging members and the can slides having a plurality of horizontally disposed can engaging members projecting toward each other and pivotally mounted on the slides to advance 95
35 the cans.

2. The combination with a sterilizing device for cans and covers having reciprocating slides for advancing the cans and a reciprocating member located above the can advancing slides for advancing the covers, with 100
40 auxiliary mechanism for use at the end of the can and cover sterilizing device, comprising reciprocating slides arranged parallel to each other, each of the slide members having hinged connections opposite each other to permit the remote end of the slides to be swung vertically, one end of each of the slide members having means for connecting the slides of the auxiliary mechanism to the slides of the can advancing device, said means comprising swing bolts and clevised lugs, and a slide arranged above the can advancing slide for advancing the covers, the cover advancing slide being hinged to fold upon itself and having means to connect the cover advancing slide of the auxiliary mechanism and the cover advancing slide of the sterilizer, comprising a swing bolt and clevised lug, the cover advancing slide having a plurality of dependent pivotally swinging cover engaging members and the can slides having a plurality of horizontally disposed can engaging members projecting toward each other and pivotally mounted on the slides to advance the cans.

of horizontally disposed can engaging members projecting toward each other and pivotally mounted on the slides to advance the cans.

3. The combination with a sterilizing device for cans and covers having reciprocating slides for advancing the cans and a reciprocating member located above the can advancing slides for advancing the covers, with auxiliary mechanism for use at the end of the can and cover sterilizing device, comprising reciprocating slides arranged parallel to each other and supported on frame members, the frame members being hinged and each of the slide members having hinged connections opposite each other to permit the remote end of the slides to be swung vertically, the hinged connections of the slides being located above the hinged connection of the frame, one end of each of the slide members having means for connecting the slides of the auxiliary mechanism to the slides of the can advancing device, said means comprising swing bolts and clevised lugs, and a slide arranged above the can advancing slide for advancing the covers, the last named slide being supported on a frame connected to the frame supporting the can slides, the cover advancing slide being hinged to fold upon itself and having means to connect the cover advancing slide of the auxiliary mechanism and the cover advancing slide of the sterilizer, comprising a swing bolt and clevised lug, the cover advancing slide having a plurality of dependent pivotally swinging cover engaging members and the can slides having a plurality of horizontally disposed can engaging members projecting toward each other and pivotally mounted on the slides to advance the cans.

4. The combination with a can sterilizing device having a reciprocating member having a plurality of can engaging members disposed along its length for advancing the cans, and means for supporting the member with auxiliary mechanism for use at the end of the can sterilizing device, comprising a reciprocating slide having a hinged connection to permit the remote end of the slide to be swung vertically, means for supporting and guiding the slide, one end of the slide member having means for connecting the slide of the auxiliary mechanism to the slide of the can advancing device, and the can slides having a plurality of can engaging members pivotally mounted on the slides to advance the cans, the reciprocating slides of the sterilizer and auxiliary device being adapted to be guided by both the auxiliary support and the sterilizer support.

LESTER J. WILLIAMS.
